UNITED STATES PATENT OFFICE.

VERNON BALFOUR HARLEY-MASON, OF CHEAM, ENGLAND.

CONSTRUCTION OF INTERNAL-COMBUSTION-ENGINE CYLINDERS.

Application filed May 7, 1923. Serial No. 637,306.

To all whom it may concern:

Be it known that I, VERNON BALFOUR HARLEY-MASON, a subject of the King of Great Britain, and a resident of Cheam, in the county of Surrey, England, have invented a certain new and useful Improvement in the Construction of Internal-Combustion-Engine Cylinders, of which the following is a specification.

10 This invention relates to the construction of the cylinders of internal combustion engines. As is well known the stresses set up in internal combustion cylinder walls are due to two main causes, viz., pressure of the 15 working fluid within the cylinder and difference of temperature within the thickness of the wall due to heat flowing from the hot interior to the cooling medium outside.

Increases of fluid pressure within the 20 cylinder can be met by increasing the thickness of the cylinder wall but the limit to which this thickening up can be accomplished in practice is soon reached for the reason that this increase of wall thickness, 25 while it diminishes the stresses due to the fluid pressure, increases the heat stresses due to temperature difference. It will thus be seen that opposite conditions have to be met and the ordinary practice is to make the 30 cylinder wall as thick as possible having regard to the temperature conditions and thus the diameter of the cylinders of internal combustion engines is limited by the necessity for simultaneously accommodating 35 these two conditions. In order to overcome this difficulty and increase the size to which the cylinders can be built it has been suggested to make the cylinder thin—so thin that it cannot resist the pressure stresses 40 to which it would be subjected in normal working—and support it from outside by some pressure resisting means. It is of course also well known to provide a cylinder with ribs.

45 In an internal combustion engine cylinder, the intensity of the above mentioned stresses is not uniformly distributed throughout the length of the cylinder but is greatest at that part of the cylinder where combustion takes place and rapidly falls towards the end or ends remote from the combustion zone. That portion of the cylinder wall which is exposed to very high stresses is very short.

50 That is to say the part of an internal combustion engine cylinder which is subjected to the extreme stresses due to pressure and

temperature is comparatively short in length and may be regarded as that part of the combustion space when the charge is at its maximum compression. After the 60 piston has moved a certain distance the pressure hence the stress due to pressure commences to fall and the heat stresses also diminish toward the cylinder end or ends. Thus so far as the end or ends of the cylinder 65 remote from the combustion zone are concerned the thickness of the walls can be increased without involving undue stresses.

According to my present invention I 70 form the cylinder thin at or about that part where it is subjected to the higher stresses and I strengthen this thin part by ribbing it in such a manner that the ribs are supported at each end on thicker parts of the 75 cylinder wall these thicker parts adequately accommodating the fluid pressure stresses and also in spite of the thickness being quite able to withstand the heat stresses which, as before indicated are much diminished at those parts.

Each of the ribs aforesaid constitutes a beam which may be of any suitable section and this section may vary throughout its length and the preferred arrangement is to 85 give these ribs a T headed section.

In engines of the opposed piston type, the highly stressed and heated portion occurs at or near the middle of the length of the cylinder wall and sufficient section of cylinder 90 wall to afford the necessary support is thus given on both sides of the highly stressed and heated portion.

In single piston engines however, especially in cases where a separate cylinder 95 cover is fitted, the highly stressed and heated portion occurs at one end of the cylinder barrel and it may be necessary to provide additional supporting section on one side of the highly stressed and heated section.

100 This may be done in any suitable manner, such as, for instance, producing the wall for some distance and sinking the cover into it a corresponding amount or by turning it outwards in the form of a flange or even by designing the ribs to act as cantilevers instead of beams.

110 In the accompanying drawings I have illustrated embodiments of my invention Fig. 1 being a longitudinal section of the combustion end of a cylinder wall constructed in accordance with my invention.

Fig. 2 is a transverse section on the line 2—2 of Fig. 1. Fig. 3 is a longitudinal section of a cylinder wall for an engine of the opposed piston type constructed in accordance with my invention and Figs. 4 and 5 are fragmentary views illustrating some of the forms the ribs may take in section.

Referring to these drawings throughout which like numerals of reference indicate corresponding parts the numeral 1 designates the cylinder wall which is made thin—by which is meant it is not sufficiently thick to withstand the combustion pressures unaided—and this "thin" part which, of course, surrounds the combustion zone is strengthened by means of ribs 2 which surround it, these ribs being anchored to thickened portions 3 and 4 of the casting. If desirable these ribs may be further supported at or adjacent to the pressure zone by a reinforcing hoop 5 as indicated in Fig. 3 of the drawings, in accordance with the principle outlined in British Letters Patent No. 1750 of 1912 granted to William Joseph Still.

As before mentioned the ribs 2 may be of

any desired section and the section may vary at different positions throughout their length and in Figs. 4 and 5 I have illustrated special sections which may be adopted the T section shown in Fig. 2 being the form I 30 regard as most suitable in general.

Further these ribs may be arranged either parallel to the axis of the cylinder as shown or may be inclined at some suitable angle thereto.

What I claim and desire to secure by Letters Patent is:—

1. A cylinder for internal combustion engines having that part of its wall which in the operation of the engine is subjected to the higher temperature and pressure stresses formed thin and strengthened by integral ribs connected to thicker parts of the cylinder wall.

2. A cylinder for internal combustion engines according to claim 1 and in which the ribs are reinforced by a strengthening band encircling or adjacent to the pressure zone.

In witness whereof I affix my signature.

VERNON BALFOUR HARLEY-MASON.
